CLAIM

The ornamental design for a surgical handpiece, as shown and described.

DESCRIPTION

FIG. 1 is a right, rear perspective view of a surgical handpiece showing my new design;

FIG. 2 is a right side elevational view thereof;

FIG. 3 is a rear elevational view thereof;

FIG. 4 is a front elevational view thereof;

FIG. 5 is a left side elevational view thereof;

FIG. 6 is a top plan view thereof; and,

FIG. 7 is a bottom plan view thereof.

The handpiece of the present invention is used during microsurgery, particularly ophthalmic surgery, to irrigate and aspirate the surgical site. The handpiece is a hand-held surgical instrument that is connected to a control system through irrigation and aspiration tubings.
